United States Patent

Des. 239,487
Patented Apr. 13, 1976

239,487

TABLE

Jack H. Hysten, 1402 Chandler St.,
Topeka, Kans. 66607

Filed Dec. 17, 1973, Ser. No. 425,640

Term of patent 14 years

Int. Cl. D6—03

U.S. Cl. D6—146

FIGURE 1

FIGURE 2

FIGURE 3

FIGURE 4

FIG. 1 is a perspective view of a table embodying my new design;

FIG. 2 is a front elevation view thereof;

FIG. 3 is a side elevation view thereof, looking directly at one leg thereof; and

FIG. 4 is a top plan view thereof.

I claim:

The ornamental design for a table, as shown.
